[57] **CLAIM**

The ornamental design of an aerial ball, is shown and described.

DESCRIPTION

FIG. 1 is a side elevational view of an aerial ball showing my new design in an environment;

FIG. 2 is a top plan view thereof;

FIG. 3 is a front elevation view thereof;

FIG. 4 is a bottom plan view thereof;

FIG. 5 is a rear elevation view thereof;

FIG. 6 is a right side elevation view thereof;

FIG. 7 is a left side elevation view thereof;

FIG. 8 is a front perspective view thereof with the shell open; and,

FIG. 9 is a front elevation view of an alternative embodiment thereof lined for black and white.

The top, bottom, rear, right and left side of the alternative embodiment are the same as FIGS. 2, 4, 5, 6 and 7, respectively, except for the contrasting panels;

The broken line showing of the car and aerial in FIG. 1 is for illustrative purposes and forms no part of the claimed design.
